United States Patent

Des. 236,586
Patented Sept. 2, 1975

236,586

BOTTLE OR SIMILAR ARTICLE

John W. McDonald, Kansas City, Mo., assignor to Ethyl
Development Corporation, Kansas City, Mo.

Filed Oct. 15, 1973, Ser. No. 406,563

Term of patent 14 years

Int. Cl. D9—01

U.S. Cl. D9—129

FIG. 3.

FIG. 5.

FIG. 1.

FIG. 2.

FIG. 4.

FIG. 6.

FIG. 1 is a front elevational view of a bottle embodying my new design;

FIG. 2 is a side elevational view thereof;

FIG. 3 is a top plan view thereof;

FIG. 4 is a bottom plan view thereof;

FIG. 5 is a cross-sectional view of FIG. 1 taken along line 5—5; and

FIG. 6 is a cross-sectional view of FIG. 1 taken along line 6—6.

I claim:

The ornamental design for a bottle or similar article, substantially as shown.
